UNITED STATES PATENT OFFICE.

JACOB SODERBERG, OF PITTSBURGH, PENNSYLVANIA, ASSIGNOR TO PITTSBURGH PLATE GLASS COMPANY, A CORPORATION OF PENNSYLVANIA.

GRINDING APPARATUS FOR PLATE GLASS.

Application filed July 28, 1923. Serial No. 654,477.

To all whom it may concern:

Be it known that I, JACOB SODERBERG, a citizen of the United States, and a resident of Pittsburgh, in the county of Allegheny and State of Pennsylvania, have made a new and useful invention in Improvements in Grinding Apparatus for Plate Glass, of which the following is a specification.

The invention relates to grinding apparatus for plate glass and particularly to apparatus for use in a straightaway operation in which the glass is carried in a continuous sheet or ribbon or in a series of sheets upon tables or carriers beneath a series of grinding machines. The invention has for its principal object the provision of improved means for grading and supplying abrasive to the system involving the series of grinding machines as above specified, such means being arranged so that abrasive of the proper degree of fineness may be supplied to all the various machines, and so that a high degree of economy in the use of the abrasive is secured. One embodiment of the invention is illustrated in the accompanying drawings wherein:

Figure 1 is a plan view of the apparatus. Figs. 2 and 3 are sections on the lines II-II and III-III respectively of Fig. 1. Fig. 4 is an enlarged detail section through the siphon outlet at the top of one of the tanks. Fig. 5 is an enlarged section through the outlet at the top of the first grade tank of the series. And Figs. 6 and 7 are detail views showing the scraper or squeegee used intermediate the various grinding tables.

Referring to the drawings, 1 to 15 are a series of grinding machines arranged in sets of five, the first set, 1 to 5, being supplied from a grading tank 16, the second set, 6 to 10, being supplied with abrasive from the tank 17 and the third set, 11 to 15, being supplied with abrasive from the grading tank 18. The grinding machines are preferably of the type illustrated in Figs. 2 and 3, comprising a runner 19 carried by a shaft 20 driven from a motor 21 through the intermediary of reduction gearing in the casing 22. The runner and its driving mechanism is supported for vertical movement upon a lever 23 whose position is controlled by means of the rod 24 which is threaded at its lower end and worked up and down by means of a nut 25 provided with a suitable hand wheel. This particular

form of grinding machine constitutes no part of my invention, as any other type might be substituted. Extending beneath the series of machines are the tracks 26 upon which are mounted a series of cars 27 carrying upon their upper sides the sheets of glass which are to be ground. These cars are carried along beneath the series of grinding runners at a uniform speed by any suitable form of mechanism. The tracks are preferably mounted upon a concrete foundation 28 which is formed so as to provide splash walls 29 at the sides of the table and suitable drainage ditches 30 whereby the used abrasive and water from the cars or tables may be returned to the sumps beneath the grading tanks.

The grading tank 16 is preferably of the conical form indicated in Fig. 2 and is supplied from a sump 30 by means of a pump 31 having the inlet 32 projecting into the sump. The sump itself is supplied with green or new sand from time to time from the elevated bin 33 provided with an outlet 33^a leading into the sump, and the bin itself is supplied with sand, either by means of an overhead bucket arrangement, or by means of the elevator 34 adapted to raise the sand from the pit 35.

Since the first five machines of the series are designed to perform the rough grinding operation, it is not necessary that the sand should be separated into different grades for these machines, so that all the abrasive for these five machines is taken from the same level in the grading tank 16 by means of the pipe 36 which discharges into a box 37 from which the pipes 38 lead to the various runners and discharge to the openings 39 through the centers thereof. The box 37 is provided with an overflow compartment 40 (Fig. 5) and the pipe 41 from this overflow leads back into the sump 30. In order to control the flow through the various pipes 38, the ball valves 42 are preferably employed, such valves being moved up and down by means of the chains 43. In order to agitate the mixture of sand and water in the compartment 37, a supplemental pipe 44 leading from the water main and having a controlling valve 45 may be employed. The tank is also provided with an overflow 46, so that sand which is too fine for use and the surplus water may be carried to the drain 47 leading from the ditch beneath the

tables to the sump 48 of the next grading tank 17.

By reason of the conical form of the tank 16, the velocity of the water decreases from 5 the lower end of the conical portion to the upper portion, and by adjusting the speed of the pump 31 the pipe 36 will withdraw only the coarsest abrasive, the finer abrasive rising above the lower end of the pipe 10 and discharging through the outlet 46 for use in the next tank in which finer grades of sand are required.

The used sand from the first five tables together with the surplus water is discharged into the drain 47 leading to the sump 48 from which the grading tank 17 is supplied. This grading tank is also of conical form as indicated in Fig. 3 and is supplied from the sump by means of the pump 49 through the pipe 50. The contents of the tank is withdrawn through the pipes 51, 52, 53, 54 and 55, all leading from different levels in the tank as illustrated in Fig. 3. The abrasive withdrawn from the pipe 20 51 is the coarsest and this is conducted to machine 6, the abrasive from the pipes 52 to 55 being successively finer and being conducted to the machines 7, 8, 9 and 10. The material is withdrawn from the pipes 51 to 30 55 by means of the siphon arrangement shown in Fig. 4, the pipe 53 as here shown extending through the side of the tank to the downwardly extending pipe 56 which carries on its lower end the sleeve 57, adjustable vertically and held in position by means of the set screw 58. The sleeve discharges into a funnel 59 carried by the upper end of one of the series of pipes 60 which lead to the grinding table. The use of the sleeve 35 57 permits of the adjustment of the head upon the liquid discharging through the siphon so that the velocity of flow may be controlled to suit requirements. Additional water may be supplied to the pipe 56 to 40 agitate the mixture by means of the small water pipe 61. The overflow from this tank passes through the pipe 62 to the drain 63 leading to the sump 64 of the third grading tank of the series, so that the excess water 45 and abrasive too fine for use are carried on to the next set of machines which require the finest sand. The sand which collects in this tank 17 which is too coarse for use in the machines supplied by the tank is returned to 50 the sump of the tank 16 by means of a pipe 65 leading from a point below the lower end of the lowest pipe 15.

The last five grinding machines 11 to 15 are supplied from the tank 18 by means of 55 the pipes 66 which are fed from siphon pipes leading to different levels in the tank 18, the same as in tank 17, this tank also being conical and being arranged throughout the same as tank 16 except that the 60 angle between the sides of the cone is pref-

erably more acute. The sump 64 is supplied with abrasive and water by means of the drain 63 leading from the ditch of the grinding machines. This tank 18 is also provided with an overflow 67 by means of 70 which the sand too fine for use and the mud may be discharged to the settling pit 68, which settling pit also receives the discharge from the drain 69 at the end of the series of machines 11 to 15. This settling pit is provided with an overflow 70 leading to the sewer and also with a water return pipe 71 leading back to the sump 30^a of the first tank 16 so that there will be no unnecessary waste of water. The tank 18 is also provided with a pipe 72 corresponding to the pipe 65 described in connection with the tank 16 and serving to return the abrasive which collects in the tank 18 which is too coarse for use to the sump 48 of the tank 17. The pipes 72 and 65, thus serves to relieve 80 the tanks 18 and 17 of abrasive too coarse for use in such tanks, which abrasive might otherwise collect to such an extent that it would modify the velocity of flow through the tanks, thus changing the character of the abrasive discharged through the siphon pipes. This also involves economy as the abrasive which is too coarse for use in one tank is carried back and used in the tank 90 next preceding in which it may be utilized.

In order to prevent the sand used with the machines 1 to 5 passing along with the tables to the machines of the next series, a squeegee device or scraper 73 is employed 100 between machines 5 and 6. Similar devices 74, 75, etc. are provided between all of the machines following 6, the purpose being to prevent sand, which is too coarse, from being carried along, as such sand tends to scratch the glass and retard the smoothing operation. This scraper device is preferably of the construction illustrated in Figs. 6 and 7, consisting of a pair of inclined frame members 76 to which are secured the rubber sheets 77 bearing at their edges upon the surface of the glass 78. The ends of the members 76 are turned forwardly as indicated at 79 and are pivoted at 80 to suitable brackets carried upon the splash walls 110 extending along the drains 30. Any other suitable means might be employed for accomplishing this function.

The operation of the apparatus will be readily apparent from the foregoing. Each 120 of the tanks 16, 17 and 18 supplies its set of machines with different grades of abrasive gradually tapering off from the coarsest grade which is supplied to the machines 1 to 5 to the finest grades which are supplied to the last set of machines 11 to 15, the machine 15 receiving the very finest sand preliminary to the application of emery or some finer material for the smoothing operation. It will be understood that 125 130

the invention is not limited to the use of any particular number of grinding machines and that the number of machines in each set supplied from a single grading tank may be varied to meet requirements. The used abrasive coming from machines 1 to 5 is supplied to the sump of the next tank 17 so that there is no loss of abrading material. Similarly the used abrasive from 10 the second set of machines is supplied to the third tank 18 for use in the last set of machines. Furthermore, any material discharged from the machines which is too coarse to be used in the next tank is returned to the preceding tank so that there is no loss of this coarse material and it is eliminated from the tank in which it might otherwise cause interference with the finer grades. Finally the surplus water from the 15 settling pit and any fine sand which might be useful in the tank 16 is returned through the pipe 71 to the sump of the tank 16 and eventually finds its way back again to tank 16 for reuse. The system is thus made 20 economical throughout, the only sand which is discharged to the sewer being that which is too fine for use in any of the tanks.

What I claim is:

1. In combination in grinding apparatus, 30 a series of sets of grinding machines, means for carrying sheet glass continuously beneath the series of machines, a series of grading tanks, one for each set of machines, means for causing an upward flow of liquid through each of the tanks to grade the abrasive therein, means for supplying the graded abrasive from each tank to its set of grinding machines, and means for supplying the used abrasive and water from the 35 first set of grinding machines to the tank for the next set of machines.

2. In combination in grinding apparatus, 40 a series of sets of grinding machines, means for carrying sheet glass continuously beneath the series of machines, a series of grading tanks, one for each set of machines, means for causing an upward flow of liquid through each of the tanks to grade the abrasive therein, means for supplying the graded abrasive from each tank to its set of grinding machines, means for supplying the grades too fine for use in the first 45 grading tank in the series to the second grading tank for supplying the second set of machines, and means for supplying the used abrasive and water from the first set of grinding machines to said second grading tank.

3. In combination in grinding apparatus, 50 a series of sets of grinding machines, means for carrying sheet glass continuously beneath the series of machines, a series of

grading tanks, one for each set of machines, means for causing an upward flow of liquid through each of the tanks to grade the 55 abrasive therein, means for supplying the graded abrasive from each tank to its set of grinding machines, and means for supplying the used abrasive and water from each set of machines (except the last set) to the 60 grading tank for the next succeeding set of machines.

4. In combination in grinding apparatus, 65 a series of sets of grinding machines, means for carrying sheet glass continuously beneath the series of machines, a series of grading tanks, one for each set of machines, means for causing an upward flow of liquid through each of the tanks to grade the 70 abrasive therein, means for supplying the graded abrasive from each tank to its set of grinding machines, means for supplying the used abrasive and water from each set of machines (except the last set) to the 75 grading tank for the next succeeding set, 80 and means for returning the used abrasive and water from the last set of machines to the grading tank for the first set.

5. In combination in grinding apparatus, 85 a series of sets of grinding machines, means for carrying sheet glass continuously beneath the series of machines, a series of grading tanks, one for each set of machines, means for causing an upward flow of liquid through each of the tanks to grade the 90 abrasive therein, means for supplying the graded abrasive from each tank to its set of grinding machines, means for supplying the used abrasive and water from the first 95 set of grinding machines to the tank for the next set of machines, and means for returning the abrasive too coarse for use with the second set of machines to the tank for the first set.

6. In combination in grinding apparatus, 100 a series of sets of grinding machines, means for carrying sheet glass continuously beneath the series of machines, a series of grading tanks, one for each set of machines, 105 means for causing an upward flow of liquid through each of the tanks to grade the abrasive therein, means for supplying the graded abrasive from each tank to its set of grinding machines, means for supplying the used abrasive and water from each 110 set of machines (except the last set) to the grading tank for the next succeeding set, and means for returning the abrasive too coarse for use from each tank after the first 115 one to the next preceding tank.

In testimony whereof, I have hereunto 120 subscribed my name this 18th day of July, 1923.

JACOB SODERBERG.
